POSTURE IMPROVING DEVICE

Forrest D. Cason, San Antonio, Tex.

Application October 31, 1951, Serial No. 254,023

16 Claims. (Cl. 128—44)

The present invention relates to means and method for the correction of defective posture.

It is an object of the invention to provide means to relax completely the muscles of the body.

It is an object of the invention to relax particularly those muscles of the body which are related to posture and are under a more or less continuous strain.

It is an object of the invention to provide apparatus to move the bony structure comfortably in such a manner as to assist the body in the restoration of posture to normal.

It is an object of the invention to provide a device upon which the body may be placed in a reclining position, the pelvis elevated, the head raised and the back arched, relaxing the muscles in the abdominal area.

Upon the departure of the pelvis from the vertical plane by sloping or tilting forward, the base of the spine or the base of the sacrum inclines forward also carrying the lower vertebra forward with it. Under these conditions it is necessary for the normal curves of the upper spine to change so the body can maintain its equilibrium. This adaptation necessitates a change in the position and action of the muscles together with the position of the internal organs and results in a body unable to function properly. The change in the position of the bony structure increases the distance between the origin and insertion of many muscles, placing them under continuous strain. With this continuous strain added to the normal demands of living these muscles tire easily. Other muscles have the distance between their origin and insertion reduced and lose much of their function. From the above it may be seen that in many cases the posture is an indication of general bodily health. Accordingly, it is an object of the invention to move and manipulate the bony structure in such a way as to assist the body in the restoration of posture to normal by relaxing the strained muscles and restoring tone to others by giving them their share of the bodily load.

To achieve the above result the machine incorporating the invention is so constructed that when the body is placed on it in a reclining position, the pelvis is elevated on a posterior incline above the low point of the spine and the head is raised. This arrangement arches the back and relaxes the muscles in the abdominal area. In this position the weight of the body in the pelvic region rests on the ischial-tuberousities and exerts a force which tends to return the pelvis to the vertical plane. The tuberousities act as pivots for the pelvic rotation. It is desired to have the shoulders and thoracic region of the body recline on a slope of about thirty degrees above the horizontal with the weight supported on two parallel raised surfaces which exert an upward and inward force on the ribs at a point removed from the transverse processes of the vertebrae, allowing freedom of movement to the articulations of the vertebrae of the spine.

The head and neck are preferably supported by an adjustable head rest. The thighs are held in an adjust-

2

able movable framework which holds the legs in a comfortable position so that the maximum relaxation of the muscles can be obtained.

The posterior incline supporting the pelvis and the adjustable framework for the thighs are both carried by a reciprocating platform mounted on rollers.

The machine may be operated with two electric motors. A small motor of about one twenty-fifth horsepower with an eccentric load on its shaft is mounted beneath the thigh rest and imparts a vibratory movement through the framework to the inner, outer and the hamstrung muscles which are relaxed and release their downward pull on the pelvis.

A larger motor of about a quarter horsepower reciprocates the platform on which the pelvis and thigh supports are mounted. The reciprocation of the platform on wheels or rollers to and from the head rest imparts an upward as well as headward movement to the pelvis because of the rotation of the pelvic rest under the action of a pivoted lever. This movement gently rocks the pelvis back to normal position. The above reciprocation also has a flexing and relaxing action on the spine in its arched position between the fixed head rest and the moving pelvic rest. The amount of movement applied is completely adjustable both in the displacement of the platform and length of the pivoted link and is to be determined by the number of spinal segments free for adaptations.

The cyclic movement of the spinal segments and the flexing and relaxing of the muscles attached to the spinal segments coupled with the pelvic movement relieves the strain on all these muscles, allows an ample supply of blood to bathe the muscle fibers and yields a progressive increase of movement in all articulations. It has also been found that the cartilage between the spinal segments regains more and more of its normal elasticity. All surfaces of the machine are carefully upholstered with foam rubber which applies the forces resulting from the movement of the machine gently to the body without substantial slipping and acts as a lost motion adjustment which absorbs that portion of the motion of the machine which the body is unable to follow due to lack of elasticity. This light gripping action eliminates friction burns due to repeated sliding. It is emphasized that the motions of the machine must be capable of delicate adjustments or grave harm may be done to the joints and ligaments in many cases.

Under treatment by the machine with the cyclic movement of flexing and relaxing the muscles receive an ample supply of fresh blood and are able to assume new positions progressively toward normal as the vertebrae are freed of adaptations and the body increasingly regains normal posture and balance.

From the above it will appear that it will be an object of the invention to provide apparatus having a thigh rest adjustable in size mounted on sponge rubber, which engages the outer, inner and hamstrung muscles of the upper thigh with a small motor having an eccentric load mounted underneath which imparts vibratory movement to the muscles of the upper thigh, causing them to relax and to release the downward and forward pull they exert on the pelvis when strained or maladjusted.

It is an object of the invention to provide apparatus having a reciprocable horizontal surface mounting a pivoted pelvic inclined support and a thigh rest supporting the lower portion of the body to use the ischial-tuberousities of the pelvis as a leverage to rock the pelvis toward a vertical position and flex the spine, moving the segments and articulations.

It is an object of the invention to provide a rest for the pelvis on an incline which has its low portion toward

the head, with raised surfaces which support the weight of the pelvis and lumbar region on the ischial-tuberousities and the apex of the sacrum so that the pelvis posterior is rocked toward normal under both the action of gravity and the effect of the cyclic upward and headward movement of the distal edge of the pelvic rest which also causes a posterior flexing of the spine.

It is an object of the invention to provide an incline sloping upwardly toward the head and providing support for the shoulders and back by means of two parallel raised surfaces that are so spaced that they exert an upward and inward force on the ribs just distal to the transverse processes of the vertebrae giving freedom of movement of the articulations in the cyclic flexing of the spine.

It is an object of the invention to provide a head rest which may be positioned to suit the height of a patient, is adjustable for comfort and provides pad support for the head with a sponge rubber pad at the top serving to hold the head stationary and exert a light pressure on the top of the head to assist in the flexing action of the spine in the cyclic headward movement. The sponge rubber pad at the top of the head serves also to absorb any portion of the headward movement not taken up by the flexing action of the spine or movement of the body relative to the reciprocating platform.

In the drawings:

Figure 1 is a perspective of one form of the device.

Figure 2 is a kinematic detail partly in section of one form of the reciprocation control.

Figure 3 is a fragmentary perspective of one form of head rest.

Figure 4 is a fragmentary view of the head rest adjustment mechanism of Figure 1.

Figure 5 is a fragmentary sectional view of the head rest of Figure 3.

Figure 6 is a fragmentary sectional view of the thigh rest.

Figure 7 is a fragmentary sectional view of another thigh rest construction.

The form of device embodying the invention illustrated comprises a framework 10 of wood, angle iron or tubing, having a bed 11 supported by upright legs 12 and 13 and 14 braced in a suitable manner. Upright 14 projects beyond bed 11 at 16 and serves to support the upper end of head incline 17 which is pivoted on bed 11 at 18. Head incline 17 makes an angle of about thirty degrees with bed 11.

At the upper end of head incline 17 is mounted a movable head rest 15 in Figure 1 and 19 in Figure 3. Rest 19 has foam rubber pads 20, 21 and 22 supported by a frame work 23, the arms of which may be made resilient. Foam rubber pad 20 has about four and a half inches of foam rubber so as to absorb the headward thrust of the cyclic movement which the elasticity of the body cannot accept without discomfort. Frame 23 is supported on stem 24 which slides within mounting 25 and may be adjusted by set screw 26. Mounting 25 is slidably held between runway guides 27 and may be moved up or down head incline 17 to suit the height of the patient being treated. Screw member 28 serves to lock mounting 25 in any desired position in guides 27 by a wedging action against the walls of runway guides 27.

On head incline 17 outside of guides 27 are two elongate projecting bars 30 which extend along the middle half of incline 17 as shown in Figure 1. Bars 30 provide parallel spaced surfaces which are so spaced that in reaction to the bodily weight they exert an upward and inward force on the ribs just distal to the transverse processes of the vertebrae.

Bars 30 are suitably upholstered with sheet sponge rubber and the whole head incline 17 is covered with a suitable moisture proof layer such as any of the plastic leather substitutes. Bars 30 are two parallel lengths of wood an inch and a quarter square covered with sponge rubber. They help spring the ribs upward and forward,

cause movement and tend to correct adaptations of the ribs. This increases the capacity of the chest, giving more room for the lungs and heart. It is within the spirit of the invention to provide means to adjust the angle of inclination of head incline 17 to bed 11.

A horizontally reciprocable platform 31 is preferably mounted on arms 30 pivoted to each corner thereof and to the bottom of frame 10 by sealed-in-grease bearings 31. At the head end of platform 31 pelvic rest 34 is pivoted at 35. The opposite end of rest 34 is connected to bed 11 by an adjustable link 36. Link 36 is pivoted at one end at 37 to pelvic rest 34 and at the other end to bed 11 at 38. Pelvic rest 34 is arranged to oscillate about the position of approximately thirty degrees inclination to platform 31 and has a positive slope while head incline 17 has a negative slope.

A thigh rest 39 is mounted on platform 31 adjacent pelvic rest 34 and comprises an angular structure 40 with two valleys 41 to receive the patient's thigh and a central raised portion 47. A transverse rod 42 is mounted in structure 40 and serves to move it bodily as shown by the dotted line in Figure 6. Controlled movement is obtained by connecting rod 43 which joins rod 42 with crank 44 of motor 45 mounted on the under side of platform 31. Guides 46 serve to keep rest 39 in position on platform 31.

As shown in Figure 7 central raised portion 47 may be separate from the remainder of the angular structure 40 which becomes three parts, the outside ones 60 being fastened to platform 31 and the central part 61, formerly part 47 resting on rubber cushion supports 62 mounted on the top platform 31 as shown. A motor 48 with an eccentric weight 63 is attached to an inside surface of central part 61 and serves to vibrate it to a desired degree by variable speed motor 48.

Platform 31 is reciprocated by means of a motor 49 which turns crank 52 by means of a gear box 51. Link 50 joins the upright member 65. The upper end of member 65 is connected to upright 13 by an anchoring link 66. Depending arms 67 connect the platform 31 with upright 65 through a sleeve 68 which is slidable on the member 65. Upright 65 pivots about the movable pivot at the end of link 66 and moves sleeve 68 back and forth to reciprocate or otherwise move platform 31. The sleeve experiences a small movement relative to vertical arm 65.

Where the sleeve 68 and arms 67 do not support the upright member on vertical 65 this function may be accomplished by an additional linkage arrangement comprising links 69, 70, 71 and 72 shown in Figure 2. Slide 73 permits movement of arm 72 and the rest of the supporting linkage. Where linkage 69-73 is dispensed with, a free assembly of the parts 65 and 68 and rounding thereof for ease of relative movement is recommended. For example the rounded end of link 66 connected to the upper end of member 65 may rest and slide on the upper surface of sleeve 68. The inside of sleeve 68 may be rounded to allow for the relative movement if desired.

It will be understood that the effective throw of cranks 52 and 44 can be varied by successive or adjustable pin and hole connections similar to those shown, but displaced to a smaller or larger radius. The range of adjustment need not be large. The same is true of adjustable link 36.

The operation of the device is as follows: The body is placed on the device with the thighs positioned in valleys 41, the back on head incline 17 and the pelvic region resting on pelvic incline 34. Crank arm 52, arm 54 and link 36 are adjusted for minimum motion. Where mass 63 is substituted for crank 44 and connecting rod 43, a small mass 63 is used initially. The head rest is adjusted by means of set screws 26 and 28 for comfort and suitable treatment angle. After these adjustments one or both of motors 45 and 49 are operated at low speed. After initial operation at slowest speed, all of

the adjustments are checked and the amplitudes of the back and forth movement of platform 31, the up and down movement of thigh rest 39 and the angular oscillation of pelvic rest 34 are adjusted for the particular treatment being given. It will be seen from the kinematics of the linkage that the angle of rotation of pelvic rest 34 is a function of the amplitude of displacement of platform 31 and allowance must be made accordingly. The adjustment of link 36 should be made with care.

The control of amplitude is supplemented by a frequency control such as suitable rheostats in the circuits of the motors 45, 48 and 49. In general the mass and eccentricity are selected for an optimum value in relation to the horsepower of motor 48 and the rheostat adjustment is sufficient for most treatments. As the rheostats are advanced the power applied is increased as well as the numbers of oscillations per second of the several cyclic movements.

The present invention is not one that may be used recklessly or by those without knowledge of body structure and function. Much harm can be done by improper use as in cases of progressive and advanced arthritis where dangerous irritations must be very carefully guarded against. There are cases in which the necessary relaxation must be obtained in other ways rather than by the forced manipulation of the machine, gentle though it may be. However, the machine is highly beneficial when properly applied to problems of body posture.

The mounting 40 for thigh rest 39 may be made of sponge rubber, allowing a greater degree of freedom of vibration. Motor 49 may be connected to gear reduction box 51 by flexible coupling.

While there have been described above what are at present believed to be preferred forms of the invention, it will be understood that other embodiments thereof falling within the true spirit may occur to those skilled in the art in the light of the present disclosure. All such variations as fall within the generic terminology of the following claims are intended to be covered thereby.

I claim:

1. In a device for improving posture, a frame, a thigh rest movably mounted for movement of translation on said frame, said thigh rest proportioned to engage the outer, inner and ham string muscles of the upper thigh, a motor mounted on said thigh rest and arranged to impart vibratory movement through said rest to said muscles whereby the muscles of the upper thigh may be completely relaxed, all subconscious tensions released and any downward and forward pull on the pelvis by said muscles released.

2. The combination set forth in claim 1, said thigh rest being mounted on said frame by resilient means and said motor being mounted on the underside of said thigh rest.

3. In a device for relaxing body muscles, a frame member, bed means reciprocably mounted on said frame member, means on said bed means to support the lower portion of the body, means on said frame to support the upper part of the body, and means to reciprocate said bed means.

4. The combination set forth in claim 3, said means on said bed means comprising a thigh rest and a pelvic incline mounted for differing movements.

5. The combination set forth in claim 3, said means on said bed means comprising a pelvic incline and a thigh rest, mounted to reciprocate cyclically with said bed means, means acting on said pelvic incline simultaneously to move it upward and headward whereby the ischial-tuberosities are used to rock the pelvis toward the ver-

tical position, causing flexing of the spine and movement of the segments of the spine.

6. In apparatus of the character described, mounting means, an incline for the upper portion of the body, a pelvic incline, said inclines being carried by said mounting means and being related as the sides of an obtuse angle adapted in conjunction with said mounting means to support a human body and means acting on one of said inclines to vary the angular relation of said inclines.

7. The combination set forth in claim 6, said pelvic incline being pivoted adjacent its lowest point, said last named means acting to rotate said pelvic incline about its pivot.

8. The combination set forth in claim 6, a reciprocating platform carried by said mounting member, said pelvic incline being pivoted adjacent its lowest point to said platform and link means connecting said mounting member and said pelvic incline at a point removed from its pivot whereby said pelvic incline is pivoted about a moving pivot, the pelvis is rocked and the spine flexed.

9. A machine for improving posture comprising, frame means, a head incline, adjustable head supporting means mounted on said head incline, a reciprocating platform, means to reciprocate said platform, means to adjust the distance of travel of said platform, a pelvic incline pivoted to the head end of said platform, link means connecting the free end of said pelvic incline and said frame means, a thigh rest mounted on said platform with sponge rubber, and a motor having an eccentric load mounted on said thigh rest whereby the muscles of the body are all relaxed and the pelvis is permitted to regain the vertical and means to vary the speed of said motor.

10. The combination set forth in claim 9, said head incline having two parallel raised surfaces spaced to exert an upward and inward force on the ribs.

11. A machine for improving posture comprising, a mounting frame, a fixed inclined support for the upper portion of the body carried by said frame, an adjustable head support mounted on said fixed inclined support, reciprocating means carried by said mounting frame, an inclined pelvic support pivoted to said reciprocating means, means coacting with said frame and said pelvic support acting to rotate the pelvic support about its pivot upon reciprocation of said reciprocating means and means to vary the amplitude and frequency of movement of said reciprocating means and said pelvic support.

12. The combination set forth in claim 11, a vibratory thigh rest mounted on said reciprocating means adjacent said pelvic support.

13. In a machine of the character described, an inclined pelvis rest mounted for controlled movement of rotation and translation.

14. In a machine of the character described, a fixed head support and means to rock the pelvis upward and backward toward said head support whereby the spine is flexed, muscles relaxed and circulation promoted.

15. In a machine of the character described a frame having moving pivot means mounted thereon, a pelvic support pivoted on said moving pivot means, means to move the pivot means, and means to rotate said pelvic support about said pivot.

16. The combination set forth in claim 15, means to control the degree of rock of said pelvic support.
